NOZZLE CONSTRUCTION

Clifford C. Vanderwall, Marinette, Wis., assignor
to Ansul Chemical Company, Marinette, Wis.,
a corporation of Wisconsin

Application October 5, 1951, Serial No. 249,874

3 Claims. (Cl. 169—1)

1 This invention relates to a nozzle construction for producing streams of predetermined shape and velocity. More specifically, the invention relates to the production of streams of comminuted free-flowing fire-extinguishing dry chemical. The nozzle construction of the present invention is particularly adapted for producing streams of gas-fluidized dry chemical adapted for extinguishing gasoline, kerosene and paraffin oil fires, the dry chemical being propelled through the nozzle by an inert gas, such as nitrogen or carbon dioxide under high pressure.

Further objects and advantages of the invention will be apparent from the following specification and appended drawings, wherein

Figure 1 is a plan view of one specific type of nozzle embodying the novel features of the present invention.

Figure 2 is a front end view of the discharge end of the nozzle shown in Figure 1.

Figure 3 is a side view of the nozzle shown in Figure 1.

Figure 4 is a vertical sectional view of the nozzle shown in Figure 1 having the plunger in closed position.

Figure 5 is a sectional view of the nozzle shown in Figure 1 having the plunger in open position for stream emission.

Figure 6 is a sectional view taken on lines 6—6 of Figure 5.

Figure 7 is a perspective view of the plunger, and

Figure 8 is a perspective exploded view, partly in section, of the elements constituting the nozzle construction.

The nozzle of the present invention is particularly adapted for use with dry chemical fire extinguishing equipment. Such equipment for example may consist of a steel cylinder holding the dry chemical charge, a cylinder of nitrogen gas which provides the pressure for expelling the dry chemical and a rubber hose equipped with a nozzle construction in accordance with the present invention for controlling and directing the flow of dry chemical.

Referring to the drawings, the nozzle construction comprises a cylindrical body portion 1 provided with an internal bore for housing a slideable plunger 2 which serves to control the flow of a stream of dry chemical 10 supplied by a conduit or hose 20 connected to the nozzle body by a hose coupling 8 at its threaded end 16. The outlet bore 21 of the nozzle body is of such dimension as to receive therein the conical head 2a of an axially slideable plunger 2. The bore terminates interiorly of the nozzle in a bevelled seat 17 which is adapted to seat and accurately mate with the bevelled sealing surface 9 of the plunger 2 so as to seal the bore against passage of gas pressure and dry chemical supplied by hose 20 at the intake end of the nozzle. The intake end of the

nozzle body is provided with a bore 24 which is smaller in diameter than the outlet bore 21. The surfaces of both bores are preferably parallel with the longitudinal axis of the nozzle. The intake bore 24 is adapted to slidably receive and guide the cylindrical stem 2b of the plunger 2 for axial longitudinal movement therein. The stem is provided with grooves or channels 13, as shown in Figure 7, through which the gas and dry chemical supplied by hose 20 can pass through bore 24 and enter into the outlet bore 21 when the plunger 2 is moved toward the nozzle tip as shown in Figure 5. The head portion 2a of the plunger is conically shaped so that the inclined walls are positioned at a predetermined angle to the axis of the bore so as to direct the dry chemical streams passing through the channels 13 against the inner walls of the bore 21 as shown in Figure 5 and which are then redirected forwardly of the nozzle to join other like redirected streams and to emerge from the bore 21 at the nozzle tip to form a combined stream. It will also be noted in Figure 5 that the plunger is located at a predetermined distance from the nozzle tip so that the major portions of emerging redirected streams 11 and 12 recombine outside the nozzle tip to form a combined stream.

The shape, velocity and character of the emerging stream can be predetermined by suitable changes in the structure and location of the plunger in the nozzle bore. When two opposed channels 13 are provided, a fan-shaped stream, as shown in Figure 5, will be produced. By increasing the number of channels in the plunger stem, streams of other desired shapes can be readily produced of the character described in Patent 2,484,943.

Means are provided for manually actuating the plunger 2 which consists of a handle 6 pivoted on pin 5 passing through openings 6c in the handle. The handle is provided with a pair of opposed depending arms 6a embracing the nozzle body and the ends thereof are recessed at 6b for receiving a pin 3 which passes through opposed slots 15 in the nozzle body. Plunger 2 is provided with a hole 14 at its forward tip which is adapted to receive the pin 3 passing through the opposed longitudinally extending guide slots 15 in the nozzle body. A leaf spring 4 is attached to the nozzle body by screws 7. The free end of the spring is positioned with the under surface of the handle 6, as shown in Figure 4, thereby normally urging the handle to position the plunger in closed position, as shown in Figure 4. Downward movement of handle 6 against action of spring 4 causes it to pivot on pin 5 and transmit its circular motion via pin 3 in guiding slot 15 and operating hole 14 to forward linear motion of the plunger 2, causing the sealing surfaces 9 and 17 to separate, allowing the stream

of fluidized dry chemical to flow around plunger 2, the dry chemical being so guided and controlled in quantity and direction by grooves 13 and shape of the plunger as to impinge upon the inner walls of body 1, producing dry chemical streams 11 and 12, as shown in Figures 5 and 6. When handle 6 is released, plunger 2 returns to closed position under force of spring 4. The action of the pressurized dry chemical is to open plunger 2 but this is prevented by spring 4.

The present nozzle construction is adapted to produce a fan-shaped relatively low velocity stream of dry chemical as can best be understood by reference to Figure 5, wherein the initial stream 10 of dry chemical suspended in a gaseous medium, such as nitrogen or carbon dioxide, passing through the nozzle is subdivided into a plurality of streams, for example two streams 11 and 12, when using a nozzle having the construction shown in Figure 5.

The stream 10 is reduced in velocity as it passes through the grooves 13 of plunger 2 and is subdivided into two separate secondary streams 11 and 12 which impinge against the interior surface of the nozzle bore 21 and which are then redirected essentially forwardly of the mouth of the nozzle and combined into a unitary stream having the contour shown in Figure 5 and cross-section shown in Figure 6. It is to be noted that the two streams 11 and 12 as they emerge from the mouth of the nozzle do not impinge against each other but rather flow and merge together to produce a fan-shaped stream substantially elliptical in cross-section. In accordance with the present invention the shape, direction and velocity of the dry chemical stream can be predetermined and regulated to most effectively extinguish the flames because the velocity and shape are controlled to distribute the finely divided chemical at an adequate rate for efficient and effective extinguishment of the fire.

The present nozzle construction is adapted to produce streams similar to those produced by the nozzle construction described in Patent 2,484,943 and possesses a number of advantages thereover since a single sealing surface is utilized in the present construction which is provided by the sealing surface 9 of the plunger as compared with the necessity of a plurality of seals in the prior constructions. The single seal thus insures a high degree of protection against entry of dirt or moisture within the nozzle which might render it inoperative due to cementing action of any dry chemical present. The present nozzle construction also permits a straight line of flow of the dry chemical through the nozzle. The nozzle is simple in construction and has relatively few parts, all of which can be produced at low cost. The nozzle construction can be actuated manually and also can function automatically for safety purposes in relieving excessive pressure which might build up in the supply line because excessive pressure will displace the plunger against the normal spring pressure and permit the gas to escape from the nozzle.

The shape and character of the streams produced by the present nozzle construction can be predetermined by varying the depth of the grooves or channels 13 in the plunger 2 or by providing more than two grooves so as to produce different types of streams as shown in Patent 2,484,943.

It is to be understood that numerous changes and modifications may be made in the specific

embodiment of the invention herein disclosed and it is intended to include such modifications within the scope of the appended claims.

I claim:

- 5 1. A nozzle for producing streams of gas-expelled dry chemical having a predetermined shape and velocity comprising a nozzle body provided with a bore for housing a slidable plunger, said plunger being provided with a sealing surface, a seat in said bore adapted to mate with the sealing surface of said plunger to seal the bore against flow of gas-expelled dry chemical and means to actuate said plunger to open or closed position in said bore, said plunger being provided with a plurality of channels for permitting flow of streams of dry chemical therethrough, said plunger having a conically shaped head portion having inclined walls positioned at an angle to the axis of the nozzle bore to direct the dry chemical streams passing through said channels into impingement against the inner walls of said bore, the inner walls being substantially parallel to the longitudinal axis of said nozzle, said walls redirecting said streams essentially forwardly of the nozzle to join other like redirected streams and to emerge from said chamber while recombining the major portions of the streams outside of the nozzle to form a combined stream, the said plunger being positioned at a distance from the nozzle tip to substantially predetermine the shape and velocity of the emitted stream.
- 10 2. A nozzle for producing streams of gas-propelled dry chemical having a predetermined shape and velocity as defined in claim 1 wherein the stem of the plunger is provided with two opposed longitudinally extending channels for permitting flow of streams of dry chemical therethrough.
- 15 3. A nozzle for producing streams of gas-expelled dry chemical having a predetermined shape and velocity comprising a cylindrical nozzle body, a slidable plunger housed in the bore of said nozzle body, said plunger having a head portion and a stem portion, said head portion being provided with an opening for receiving a pin, said stem portion being provided with a plurality of channels to permit streams of dry chemical to pass therethrough, said head portion being provided with a sealing surface, a seat in said nozzle bore for mating with the sealing surface of said plunger, a pair of opposed guiding slots in said nozzle body adapted to receive a pin, said pin passing through an opening provided in the head portion of said plunger for slidably moving said plunger within said bore, a bifurcated handle pivoted on said nozzle body, the arms of said handle being in engagement with the ends of said pin extending outside the nozzle body, said plunger being adapted to be manually moved upon actuation of said handle to open position.
